UNITED STATES PATENT OFFICE

DONALD C. GROVE AND JOSEPH C. BURNS, OF BIG SPRINGS, TEXAS

WELL DRILL

Application filed May 25, 1929. Serial No. 365,882.

This invention relates to a well drilling apparatus, the general object of the invention being to provide means whereby the packing element can be readily removed and replaced in the casing by the drill stem.

This invention also consists in certain other features of construction and in the combination and arrangement of the several parts, to be hereinafter fully described, illustrated in the accompanying drawings, and specifically pointed out in the appended claim.

In describing the invention in detail reference will be had to the accompanying drawings wherein like characters denote like or corresponding parts throughout the several views, and in which:

In the drawings:

Figure 1 is a view in section and elevation showing the complete arrangement with the tool depending into the hole.

Figure 2 is a longitudinal sectional view through the bit and a portion of the drill stem.

Figure 3 is an enlarged fragmentary sectional view showing the construction and position of the packer with respect to the tool and casing when said casing and packer are about to be withdrawn.

Figure 4 is a view showing the position of the packer on the tool stem when same are being reinserted in the casing.

Figure 5 is a fragmentary sectional view through the upper end portion of the packer.

Figure 6 is a cross section taken approximately on the line 6-6 of Figure 3.

Figure 7 is a bottom plan view of Figure 3.

Figure 8 is an assembly view of elements of the packer.

Figure 9 is a like perspective view of additional elements of the packer.

In these drawings the reference character 10 designates a platform and 11 designates generally a light weight rotary for rotating the well casing 12. The casing is provided on its lower end with an enlarged shoe 13 having teeth 14 at its lower end. The reference character 15 designates generally the casing head. Associated with this is the pump pipe 16 which is connected with a pump (not shown). The reference characters 17

designates the reciprocating cable which is connected with the pump jack (not shown) and serves to raise and lower the drill tool generally designated by the reference character 18. This drill tool is of course made up of sections, Figure 2 showing two of the sections, one being designated by the reference character 19 and the other by the reference character 20.

The section 20 carries the fish tail bit and all of the sections are formed with bores for forming the fluid passage 22. The section 20 is provided with an annular keeper groove 23, adjacent a reduced portion defining an annular shoulder 24.

Referring to Figure 3 it will be seen that the shoe 13 is provided with inwardly projecting lugs 25 functioning as stops for the lower end of the packer. The packer is generally designated by the reference character 26 and is of sectional construction. For instance it includes a collar 27 at the bottom which rests on the stops 25 and this carries an upstanding sleeve 28 which embraces the complementary portion of the drill stem. Surrounding the sleeve are packing rings 29, 30 and 31. At the top of the packer is an annulus 32 which carries spring pressed balls 33 for cooperation with the aforesaid groove 23. In addition the annulus is provided with spring pressed pawls 34 which cooperate with the shoulder 24.

The reference characters 35 and 36 designate the intermediate packing elements between the annulus and the sleeve. All these elements are assembled and fastened together by bolts 37 thus providing a complete packer unit.

During the drilling operation, the shoe 13 mounted on the casing 2 is normally at a point on the stem of the drill below the shoulder 24 and the annular channel or groove 23 on said stem and the pump pressure holds the packer against the stops 25. When it is desired to withdraw the packer and the drill from the casing, said casing is raised with the result that the packer which is resting on the stops 25 in the shoe 13 will be raised with the casing on the stem of the drilling tool. The casing and packer are raised until the spring-pressed pawls 34 pass the shoulder 24 and

spring into the recess formed by said shoulder in the drill stem. The casing is then lowered but the packer is prevented from moving downwardly with the casing by reason of the 5 spring pressed pawls engaging the shoulder 24.

The stem is then withdrawn from the casing and it will be obvious that the packing will be caused to move upwardly therewith.

- 10 The section of casing to be added is then mounted on the upper end of said casing and is lowered into the hole. The packer is then adjusted on the drill stem in the position shown in Figure 4 of the drawings, in which 15 position it will be noted that the spring pressed pawls 34 are engaged on the surface of the drill stem just below the shoulder 24 and the detent balls 33 are engaging the annular groove 23. The drill and the packer 20 are then inserted in the casing and lowered thereinto, the packer being assisted in its downward movement by the pressure of the liquid thereabove in the casing. When the packer reaches the shoe 13 on its downward 25 movement in the casing it again engages the stops 24 and its downward movement is arrested but the drill is permitted to continue its downward movement as the spring pressed balls 33 will readily ride out of the 30 groove 23 and the spring pressed pawls 34 will permit passage of the drill stem and shoulder 24 in this direction, as will be understood.

It is thought from the foregoing description that the advantages and novel features 35 of the invention will be readily apparent.

It is to be understood that changes may be made in the construction and in the combination and arrangement of the several parts, 40 provided that such changes fall within the scope of the appended claim.

Having thus described the invention, what we claim as new and desire to secure by Letters Patent is:—

- 45 In a well drill of the class described, a casing, a shoe on the lower end of said casing provided with internal stops, a drill tool suspended in said casing and mounted for reciprocatory motion, said drill tool being provided with a fluid supply passage, and a packer unit embracing the drill tool and confined within said casing, adapted when in position to rest upon the stop carried by said shoe, said tool including a section provided 50 with an annular groove, said packer being provided with spring pressed balls cooperable with said groove, said section being also provided with an annular shoulder, said packer being further provided with spring 55 pressed pawls cooperable with said shoulder.
- 60 In testimony whereof we affix our signatures.

DONALD C. GROVE.
JOSEPH C. BURNS.
